UNITED STATES PATENT OFFICE.

GUY J. PETERSON, OF CYANIDE, SOUTH DAKOTA, ASSIGNOR OF ONE-HALF TO PETER N. HANSON, OF DEADWOOD, SOUTH DAKOTA.

PULVERIZER.

976,831.

Specification of Letters Patent. Patented Nov. 22, 1910.

Application filed January 11, 1910. Serial No. 537,496.

To all whom it may concern:

Be it known that I, GUY J. PETERSON, a citizen of the United States of America, residing at Cyanide, in the county of Lawrence and State of South Dakota, have invented certain new and useful Improvements in Pulverizers, of which the following is a specification, reference being had therein to the accompanying drawings.

10 My invention relates to an improvement in pulverizers employing a plurality of crushing rolls and more particularly to that class of pulverizers adapted to grinding and pulverizing stone and ore, and has for its

15 object the provision of a machine capable of subjecting the substance being crushed to grinding actions of different degrees in one operation.

Another object of my invention is to provide a new and improved means for adjusting one of the crushing rolls both vertically and laterally with respect to the other rolls.

A further object is to provide novel means for permitting one of the rolls to yield 25 slightly away from the other rolls when any matter should become jammed therebetween which it would be impossible to crush, thus saving the machine from being wrecked.

A practical embodiment of my invention 30 is represented in the accompanying drawings, in which—

Figure 1 represents a side elevation view of the machine partly in section. Fig. 2 is an end view of the machine. Fig. 3 is a detail view of mechanism for adjusting one of the rolls. Fig. 4 is vertical sectional view taken on line 1—1 Fig. 1, and Fig. 5 is a sectional view taken on line 3—3 Fig. 3.

In a suitable frame 1 inclosed by housing 40 2 are mounted crushing rolls 3, 4 and 5, the roll 4 vertically beneath roll 3 and roll 5 a little to one side of and approximately between the other two rolls. These rolls are formed of substantially cone shaped members 6 and 7 adapted to seat upon the bevelled inner faces 9, 10 of the shell 8, so that when the two members 6 and 7 are drawn together a substantially solid roll will be formed. The upper and lower rolls 3 and 50 4 are keyed respectively to shafts 11 and 12 which shafts in turn are mounted in bearings 13 and 14. The bearings 13 are provided with an externally screw threaded portion 15 for a purpose to be hereinafter de-

scribed. Each of the shafts 11 and 12 have 55 mounted thereon the belt wheels 16 adapted to be driven by a suitable source of power not shown. Adjacent the wheels 16 are gear wheels 17 meshing with gear wheels 18 mounted on either extremity of the shaft 19 60 which carries the intermediate roll 5.

Means are provided for laterally shifting the upper and lower rolls 3 and 4 with respect to each other to insure an even wearing of all parts of the crushing surfaces 65 thereof. This means consists of an internally screw threaded sleeve 21 having a shoulder 22 and an externally screw threaded portion 23 which sleeve is adapted to screw on the threaded portions 15 of the bearings 70 13. A cap 24 when screwed upon the sleeve 21 bears against the collar 25 mounted on the ends of the shafts carrying the upper and lower rollers. Preferably washers 26 and 27 are provided at opposite sides of the 75 collar 25. It will thus be seen that the screwing of the sleeve 21 and cap 24 to the right or left will result in a corresponding movement of the rolls 3 and 4.

The bearings 20 of the shaft 19 are slidably mounted in standards 28 which in turn rest upon substantially wedge shaped blocks 29 and 30 connected by dovetail and groove connections 31. Mounted in the bifurcated arm 32 of the lower block 30 is a threaded 80 pin 33 having one end fast to the upper block 29 and carrying the gear 34 meshing with the worm gear 35 on the inner end of crank 36 by means of which the block 29 85 may be moved in either direction and the roll 5 correspondingly raised or lowered. The roll 5 is also provided with means for shifting said roll toward or away from the other rolls consisting of the rod 37 having one end fixed to the standards 28 and the 90 other end thereof slidably mounted in the support 38 secured to the frame 1. The outer end of the rod 37 is screw threaded to receive the nut 39 and interposed between said nut and the support 38 is a tension 95 100 spring 40, the said spring permitting of a slight movement of the roll after the same has been adjusted.

The operation of the machine is obvious from the foregoing, but might be briefly 105 stated as follows: The substance to be pulverized being fed in the hopper 41 passes between the upper and intermediate roll and

is then directed by the shield 42 between the intermediate and lower roll and out through chute 43.

What I claim is—

5. In a pulverizer, a base frame, an upper and lower roll and an intermediate roll resilient means for moving the intermediate roll away from and toward the other rolls, means for shifting said upper and lower 10 rolls longitudinally with respect to said intermediate rolls, means for raising and lowering said intermediate roll comprising a wedge shaped block, supporting said roll

having an upwardly projecting bifurcated arm, a second wedge shaped block slidably 15 mounted upon said first named block provided with a threaded pin projecting from one end thereof, said pin working through said bifurcated arm, an internally threaded gear wheel carried by the threaded pin and 20 a worm gear carried by a crank mounted in said arm meshing with said wheel.

GUY J. PETERSON.
